ABSTRACT

A submersible pump having a vane-wheel formed with cutter means at the bottom inlet portion thereof which cooperates with cutter means which are formed on the pump casing and which are disposed below the cutter means on the vane wheel. Foreign objects pumped into the inlet openings with the liquid being pumped are cut into pieces thereby not reducing the pumping efficiency of the pump.

FIG. 5

SUBMERSIBLE PUMP EQUIPPED WITH CUTTER**BACKGROUND OF THE INVENTION**

The present invention relates as indicated to a submersible pump equipped with a cutter for pumping water or other liquid containing admixtures or foreign objects, which are cut into pieces by means of cutter blades provided therein.

In previous submersible pumps of the type having an open vane-wheel, attempts have been made to cut foreign objects by means of the gap formed between the vanes of said vane-wheel and the pump casing disposed in confronting relation thereto.

Although submersible pumps of the open vane-wheel type have the advantage of pumping water or other liquid irrespective of its admixtures, they have the disadvantage that their pumping efficiency is significantly reduced because the cutting of foreign objects is done merely by rocking them between the vanes of said open type vane-wheel and the pump casing. The pumping efficiency of such pumps is particularly low when compared with a pump using a closed type vane-wheel.

SUMMARY OF THE INVENTION

In view of the above disadvantages of conventional pumps, the primary object of the present invention is to provide a pump of high efficiency by utilizing a closed type vane-wheel in combination with cutters provided to positively cut foreign objects into pieces so that water or other liquid and its admixtures can be pumped in and out easily without substantially reducing the pumping efficiency.

The pump according to the present invention utilizes a closed type vane-wheel and foreign objects sucked in with water or other liquid are cut into pieces at the inlet portions of said vane-wheel and the pump casing by providing cutter blades respectively thereat so that it is possible for the pump to obtain a pumping efficiency as high as in the case of pure water or other liquid having no admixtures contained.

BRIEF DESCRIPTION OF THE APPLICATION DRAWINGS

The invention is described hereinbelow in detail with reference to the accompanying drawings in which:

FIG. 1 is a vertical sectional view of the pump constructed in accordance with the present invention;

FIG. 2 is a sectional view taken on line 2-2 of FIG. 1;

FIG. 3 is a view similar to FIG. 2 and shows a modified form of cutting blades on the pump casing;

FIG. 4 is a sectional view similar to FIGS. 2 and 3 showing further modified forms of cutting blades; and

FIG. 5 is a fragmentary enlarged view of a portion of FIG. 4.

DETAILED DESCRIPTION OF THE PREFERRED EMBODIMENTS

Referring now in detail to the drawings, wherein like parts are indicated by like reference numerals, and initially to the form of the invention illustrated in FIGS. 1 and 2, the submersible pump of the present invention comprises a driving shaft 1 rotated by a suitable drive-unit (not shown), a closed type vane-wheel 2, a pump casing 3, a vane-wheel cover 4, a mouth ring 5, a cutter blade 6 provided at the inlet portion 10 of the vane-wheel 2, a cutter blade 7 provided at the inlet portion

8 of the pump casing 3, outlet 9 and a circular passage 11 formed in the vane-wheel.

As can best be seen in FIG. 2, a single cutter blade 6 is connected with the peripheral inner wall forming the inlet portion 10 of the vane-wheel 2 while the pump casing 3 surrounding the bottom of the vane-wheel 2 has in its inlet portion 8 a cutter blade 7 which is connected to the inner peripheral wall forming the inlet portion 8.

FIG. 3 shows another embodiment of the invention having a construction slightly different from that of FIG. 2, with the pump casing 3 having at its inlet portion 8 a cross-shaped cutter blade 7a connected to the inner peripheral wall forming the inlet portion 8.

FIGS. 4 and 5 show another embodiment of the invention wherein the closed type vane-wheel 2 and the pump casing 3, respectively, are each formed with a plurality of cutting blades, there being two in the form illustrated, extending radially inwardly from the inner peripheral walls of the vane-wheel and casing which define the inlet openings. Thus, the vane-wheel 2 is formed with cutter blades in the form of annular projections commonly designated at 12 and the casing 3 is formed with cutter blades in the form of angular projections commonly designated at 13.

Referring now to the operation of the pump, when the closed type vane-wheel 2 is rotated by the driving shaft 1, water or other liquid is sucked in to be pumped at a lower pressure at the central part of the inlet opening of the vane-wheel, with the liquid being at a higher pressure at the outer circle of the inlet opening due to the centrifugal effect. Foreign objects pumped together with water or other liquid are cut into pieces by means of the cutter blades 6, 7 provided at the respective inlet portions 10 and 8 of the vane-wheel 2 and the pump casing 3, more particularly, by means of the cutter blade 6 connected to the inner peripheral wall of the inlet portion 10 of the vane-wheel 2 and the cutter blade 7 or 7a connected with the inner peripheral wall of the inlet portion 8 of the pump casing 3. In the FIGS. 4-5 form of the invention, the cutting is effected by means of the angular cutter blades 12 and 13 which extend radially inwardly from the inner periphery of each inlet portion 10 and 8 of the vane-wheel and the pump casing. In all of the embodiments, the cutter blades at the inlet portion 8 of the pump casing 3 serve as a fixed cutter while the cutter blades 6 carried by the rotating vane-wheel act as the rotating cutters, whereby foreign objects are cut into pieces by these cutters crossing with each other. Thus, foreign objects, after having been cut into pieces, are delivered to the outlet 9 together with water or other liquid through the circular passage 11.

The present invention thus provides a pump of high efficiency in which foreign objects are cut between each inlet portion 10 and 8, respectively, of the vane-wheel 2 and the pump casing 3 as contrasted with conventional pumps which attempt to cut foreign objects simply by rocking them in the gap between the vanes of the vane-wheel and the pump casing, with pumping efficiency thereby significantly reduced.

I claim:

1. A submersible pump equipped with cutters for cutting foreign material carried by the liquid being pumped comprising:

a. a rotating vane-wheel having a circular lower inlet portion, a circular outlet portion, and a cutter bar

carried at the circular lower inlet portion thereof, said cutter bar being flat and extending diametrically across said circular lower inlet portion in a plane perpendicular to the axis of rotation of said vane-wheel, with the area above said cutter bar being entirely open in said vane-wheel and said circular lower inlet portion likewise being open except for said cutter bar so as to minimize flow restriction through said vane-wheel,

b. a fixed pump casing having a lower inlet portion concentrically arranged around the circular lower inlet portion of said vane-wheel, said casing being formed with cutter means extending into said lower inlet portion of said casing below said cutter bar of said vane-wheel, said cutter means comprising flat

5
bar means extending diametrically across said lower inlet portion parallel to and spaced from said cutter bar carried by said vane-wheel, the lower inlet portion of said pump casing being entirely open except for said flat bar means so as to not significantly adversely affect the volume of liquid delivered to said pump, the rotation of said vane-wheel, and thus the cutter bar carried thereby, serving to cut into pieces foreign objects pumped into said inlet portions with the liquid being pumped.

2. The pump of claim 1 wherein said flat bar means of said casing comprises a generally cross-shaped cutter bar.
